UNITED STATES PATENT OFFICE

2,449,246

IRONING MACHINE

Herbert E. Page, Alhambra, Calif.

Application March 19, 1945, Serial No. 583,542

3 Claims. (Cl. 38—14)

1

My present invention has to do with ironing machines of the type commonly called mangles, employing a rotatable ironing roll and a pressing head.

In the use of such machines, it is necessary to dampen the garment or article being pressed in order for it to iron smoothly. Conventionally, this is done by the user wetting the garment and then rolling it up to allow the moisture to spread fully through the garment, after which the garment is unrolled and fed through the ironing machine. This procedure, however, is slow and tedious, requiring double handling of the articles being pressed.

It is therefore an object of my present invention to render this conventional procedure unnecessary by simple, efficient and automatic means incorporated in the ironing machine for supplying moisture to the garment as it is fed into the machine.

More specifically, it is an object to provide in such a machine means for generating steam and spraying it upon the garment as the latter is fed onto the roll, my invention also including, among its more specific objects, novel and efficient mechanism for accomplishing this end.

By way of explaining my invention I shall now describe one particular embodiment thereof which, however, is susceptible of modification within the limits of the appended claims. For this purpose I shall refer to the accompanying drawings, in which:

Fig. 1 is an end elevation showing the device in ironing position;

Fig. 2 is an end elevation similar to Fig. 1 but showing the pressing head assembly swung away from the ironing roll;

Fig. 3 is a partial plan view;

Fig. 4 is a fragmentary view showing the ironing roll driving means; and

Fig. 5 is a fragmentary section taken on line 5—5 of Fig. 3.

Referring now to the drawings, the numeral 5 denotes a bed carrying spaced pairs of uprights 6, 7 and 8. A conventional ironing roll 15 is secured upon a shaft 16 journalled in the uprights 5, the shaft being power-driven by a motor 17 (Fig. 4), and drive connection 18.

A head assembly is carried by arm 20 secured to shaft 21, the shaft being journalled in uprights 7 and projecting outwardly from the uprights at one end, as shown at 21a, to receive a manual operating handle not shown, or conventional automatic power-driven means may be employed

to rotate shaft 21. By rotation of the shaft, the arm 20 is swung about the axis of the shaft.

Secured to the arm 20 by pin 25 there is a water tank 28 having a pressure gauge G, and a filling plug 29 provided with a pressure relief valve 30. Secured to the front of the tank by webs 31, there is a pressing head 35 within which is mounted a conventional electric heating element 37.

As best shown in Fig. 5, the top side portion of the pressing head has a bore providing a chamber 40 extending the width of the pressing head, from which chamber aligned, relatively small discharge ports 41 extend so as to discharge downwardly towards the ironing roll. Water from the tank 28 is automatically supplied to the chamber 40 by the mechanism now to be described.

A pump cylinder 45 is secured by brackets 46 to an end of the tank, a piston 47 being mounted to reciprocate in the cylinder and being connected by a rod 48 to a link 49. At its bottom end the link is pivotally connected at 50 to the uprights 8. Thus it will be seen that when the arm 20 is swung between the positions of Figs. 1 and 2, the piston is caused to reciprocate in the cylinder. This movement of the arm takes place when the head assembly is swung away from and thence towards the ironing roll in the course of inserting a fresh garment between the ironing roll and pressing head.

The cylinder has a port 52 in its top end providing a seat towards the cylinder for a spring-loaded check valve 53. The port threadedly receives a closure plug 54 through which passes a conduit 55 leading into the tank. Thus on the upward movement of the piston in the cylinder, air under pressure is forced into the tank to force water therefrom through a pipe 57 leading to a valve 58, the valve in turn being connected into the chamber 40 by a tube 59.

The core of the valve 58 is rotated by a rod 60, the rod having an operating arm 62. On the outer end of the rod 60 there is secured another arm 63 to which is pivotally secured a clevis 65. A rod 67 has its top end projecting into the clevis and carries a cross pin 68 movable along slots 69 in the clevis, the bottom ends of the slots being closed to provide a stop to limit outward movement of the rod. The rod is adapted to engage at its other end an arm 70 carried by the link 49.

A spring 71 in the clevis urges the rod axially downwardly. A spring 72 around the rod and acting between rod flange 73 and a bracket 74 also urges the rod axially downwardly.

Thus when the head assembly is swung from the position of Fig. 2 to that of Fig. 1, or to the

left, the lower end of rod 67 is brought into engagement with arm 70, which pushes the rod axially upwardly against the action of springs 72, 71, which swings arm 63 and rotates valve-actuating rod 60 to open valve 58 (see Fig. 5). This permits water under pressure in tank 28 to pass into chamber 40. The heat created in chamber 40 by the heating element is sufficient to convert the water in chamber 40 into steam, which passes out through the ports 41 to be discharged against a garment being inserted between the ironing roll and the pressing head.

A stop pin 75 is provided on the head so that if it is desired to render the valve 58 inoperative and in closed position, the lever arm 62 is moved clockwise until the rod 60 is rotated sufficiently to bring the clevis 65 against the stop pin 75, this action being allowed by the movement of the rod 67 axially of the clevis. The thrust of spring 71, due to the toggle action of the arm 63 and the clevis, will retain the clevis in contact with the stop pin 75 until the lever arm 62 is moved in the opposite direction. By this means it is possible to close the valve and render it inoperative while the head 35 is swung back and forth by means of arm 20, reciprocating piston 47 to generate preliminary pressure in the tank for initial operation of the device.

I claim:

1. In an ironing machine, a base, an ironing roll rotatably mounted on the base, means for rotating the roll, a pressing head mounted for to and fro motion relative to the roll, said head having a fluid chamber and ports communicating with the chamber and disposed towards the roll, heating means in the head disposed to heat fluid in said chamber, a liquid tank carried by the head, a conduit providing communication from the tank to the chamber, a valve controlling said conduit, pump means associated with the tank and operable by virtue of each to and fro movement of the head to create pressure on liquid in the tank, and valve-actuating means operable by virtue of movement of the head toward the roll to open said valve.

2. In an ironing machine, a base, an ironing roll rotatably mounted on the base, means for rotating the roll, a pressing head mounted for to and fro motion relative to the roll, said head having a fluid chamber and ports communicating

with the chamber and disposed towards the roll, heating means in the head disposed to heat fluid in said chamber, a liquid tank carried by the head, a conduit providing communication from the tank to the chamber, a valve controlling said conduit, pump means associated with the tank and operable by virtue of each to and fro movement of the head to create pressure on liquid in the tank, valve-actuating means operable by virtue of movement of the head toward the roll to open said valve, and manually operable means for closing said valve and for simultaneously rendering the valve-actuating means inoperative.

3. In an ironing machine, a stationary base, an ironing roll rotatably mounted on the base, means for rotating the roll, a pressing head assembly pivotally mounted on the base to swing towards and away from the roll, said assembly including a pressing element and a water tank carried by the pressing head, said pressing element having therein a chamber and ports leading from the chamber to discharge towards the roll, a conduit providing communication from the tank to the chamber, a valve controlling the conduit, means for heating the chamber, an air pump cylinder secured to the head assembly, a piston reciprocably mounted in the cylinder, a rod connected at one end to the piston and connected at its other end to the base whereby to reciprocate the piston in response to swinging movement of the head assembly, a check valve-controlled conduit providing communication from the cylinder to the tank, and means operable in response to swinging movement of the head assembly to actuate said valve.
